UNITED STATES PATENT OFFICE.

RAYMOND FRITZ, OF IRVIN HEIGHTS, NEW JERSEY, ASSIGNOR OF ONE-HALF TO
EUGEN SEYDEL, OF TRENTON, NEW JERSEY.

NON-REFILLABLE BOTTLE.

1,085,582.

Specification of Letters Patent.

Patented Jan. 27, 1914.

Application filed January 10, 1913. Serial No. 741,200.

To all whom it may concern:

Be it known that I, RAYMOND FRITZ, a citizen of the United States, residing at Irvin Heights, in the county of Mercer and 5 State of New Jersey, have invented certain new and useful Improvements in Non-Refillable Bottles, of which the following is a specification.

This invention relates to improvements 10 in guards for bottles and more specifically to non-refillable bottles.

The object of my invention consists in providing a simple, inexpensive, and highly efficient valve and guard in a non-refillable 15 bottle, so designed that when the bottle has once been emptied of its contents it cannot be refilled without detection and without mutilation of the bottle.

With the above and other objects in view 20 my invention consists in the combination, arrangement, and details of construction disclosed in the specification and drawings, and then more particularly pointed out in the appended claims.

25 In the drawings, wherein similar reference characters designate similar parts throughout the respective views, Figure 1 is a vertical sectional view of the bottle showing my improvements incorporated 30 therein, Fig. 2 is a detail view, partly in section, and partly broken away, of a cap to be described, Fig. 3 is a top plan view of my invention with the cork removed, Fig. 4 is a bottom plan view of the neck of a 35 bottle to be described, Fig. 5 is a fragmental sectional view of the neck of a bottle, Fig. 6 is a detail view of a metal tie-piece to be described, Fig. 7 is an elevation of said metal tie-piece, and Fig. 8 is fragmental view of the neck of the bottle showing 40 the metal tie-piece in place thereon.

Referring to the drawings which are merely illustrative of my invention 1 denotes a bottle of any desired construction 45 which will be formed with a contracted portion terminating short of the outer end of its neck 2 so as to confine in place the ball valve 3 in a manner which will suitably prevent the ball from sticking. This ball 3 will be made of a light metal such as aluminum and will have secured thereto wire or flexible members 4 to which is fastened a relatively-smaller ball 5, made of heavier metal such as iron, and designed to have 55 such a preponderancy of weight as will be

effective in holding ball 3 seated when the bottle shall be held at an angle sufficient, otherwise, to cause ball 3 to roll out of the contracted neck 2 of said bottle. To prevent said balls from dropping out of the 60 bottle when the same shall have been manipulated, I provide a special cap. This cap is circular in cross-section and will preferably be equal in diameter to the neck 2 of the bottle so that a metal tie piece of an 65 approved construction may be caused to firmly hold the cap down on the neck of the bottle. Cap 6 is provided with a cork-receiving hollow part 7 at one end, the cork 8 resting on a base-portion 9 extending 70 transversely of said cap and being spaced slightly from the opposite end of said cap. To provide for the access of liquid through said cap a plurality of ports 10 are formed around said base-portion, said base-portion 75 being shown circular in contour and being formed integral with said cap, the supporting lugs 11 serving to hold the base-portion in position. 12 indicates an inwardly-extending flange formed integrally adjacent said base-portion so as to lie beneath said lugs 11 when the cap is in position over the neck of the bottle. Said flange 12 extends all around a shoulder 13 formed preferably integrally with the base-portion 9, but at a slight distance therefrom so as to provide a space 9' through which the liquid 80 may trickle out of the bottle passing through ports 10 which ports are formed laterally of said shoulder. The neck 2 of the bottle may also be formed with an in-turned flange 14 to provide a firm seating for a preferably cork washer interposed between flanges 12 and 14, said washer forming a fluid-tight joint when said cap is tied down upon the neck of the bottle. The metal tie-piece may be of any desired construction and will be caused to engage both the cap and the neck of the bottle, and upon the tie-piece may be impressed the private 95 seal of the bottlers or distributors. 100 For the purpose of illustration a split ring 16 is shown which is formed with the marginal inturned beads 17 and 18 fitting the grooves 19 and 20 formed respectively 105 upon the cap 6 and the neck 2 of the bottle, said split ring being formed, if desired, with the outstanding portions 21 arranged to be clamped together by means of a suitable seal 22, whereby the beads 17 and 18 will 110

remain firmly in their grooves and whereby said cap will not be removable without breaking the seal or mutilating the tie-piece.

- 5 The bottle 1 will be filled with liquid before cap 6 is secured in position, and the force of the liquid will overcome the action of the iron ball 5, when the bottle is being emptied of its contents, the aluminium ball 10 3 being prevented from dropping out of the bottle by the shoulder 13, and from dropping into the bottle by the contracted neck 2. But after the bottle has been emptied should it be manipulated at any angle for 15 the purpose of keeping a stream of liquid entrapped therein, the ball 5 will exert a pulling action upon ball 3 keeping it down upon its seat in the contracted neck 2 of said bottle, and thereby preventing the access of liquid therethrough. Any tool or 20 instrument inserted through ports 10, for the purpose of dislodging the balls would be deflected and retarded by the inturned flange 12, because engagement would have 25 to be made with the latter before it could enter the space 9'.

Numerous modifications can be resorted to from the exact details of construction herein shown, without departing in spirit 30 from the scope of the appended claims.

What I desire to claim by Letters Patent is:—

1. A device of the kind described comprising a bottle, a flaring neck formed upon 35 said bottle, said neck having a contracted portion, a ball seated in said contracted portion, a relatively smaller and heavier ball suspended from said first named ball, a cap, an inturned flange formed upon 40 the edge of said flaring neck, an inturned

flange formed upon one edge of said cap, a washer disposed between said inturned flanges, a metal tie-piece arranged to secure said member to said neck, a transversely-extending base-portion formed within and 45 at the bottom of said cap upon which is formed said last-named inturned flange, and an integral reduced shoulder formed upon said base portion projecting toward but spaced from said first-named ball whereby 50 a channel is formed between said shoulder and said cap, said base portion being formed with a plurality of ports of a width less than the width of said second-named in-turned flange.

2. A device of the character described comprising a bottle having a neck, a tubular member arranged to form an extension upon said neck, a valve seated in said neck, a base-portion formed at one end of said neck, 60 being spaced from the adjacent edge thereof, means for securing said tubular member upon said neck, a reduced shoulder formed upon said base-portion, said base-portion being formed with a plurality of ports having 65 a wall in common with said tubular member, and a terminal inwardly-extending flange formed upon said tubular member merging with said base-portion at one end and projecting at its opposite end under 70 and beyond said ports, being spaced around said shoulder to provide a channel communicating with said neck.

In testimony whereof I have affixed my signature in presence of two witnesses.

RAYMOND FRITZ.
